(57) **CLAIM**

The ornamental design for a control head for a mobile radio, as shown and described.

DESCRIPTION

FIG. 1 is an isometric view of a control head for a mobile radio showing our new design;
 FIG. 2 is a front view thereof;
 FIG. 3 is a bottom view thereof;
 FIG. 4 is a top view thereof;
 FIG. 5 is a left view thereof; and,
 FIG. 6 is a right view thereof.

The broken lines shown in FIGS. 1–6 are included for the purpose of illustrating environmental elements only and form no part of the claimed design.
